UNITED STATES PATENT OFFICE.

HOMER R. GETTLE AND CHARLES S. SCOTT, OF BLUFFTON, INDIANA.

DESIGN FOR A DISPLAY STAND.

Application filed April 3, 1924. Serial No. 9,146. Term of patent 3½ years.

To all whom it may concern:

Be it known that we, HOMER R. GETTLE and CHARLES S. SCOTT, citizens of the United States, residing at Bluffton, in the county of Wells and State of Indiana, have invented a new, original, and ornamental Design for Display Stand, of which the following is the specification, reference being had to the accompanying drawing, forming part thereof.

Figure 1 is a front elevation of the advertising device embodying our design, and

Figure 2 is a side elevation thereof.

We claim:—

The ornamental design for a display stand as shown.

HOMER R. GETTLE.
CHARLES S. SCOTT.

Witnesses:

JOHN W. CARNALL,
LORENE M. ERHART.
